United States Patent Office

Des. 218,814
Patented Sept. 29, 1970

218,814

ROADSTER

Monte Markham, 10329 Whipple,
North Hollywood, Calif. 91602

Filed Oct. 3, 1969, Ser. No. 19,611

Term of patent 14 years

Int. Cl. D12—08

U.S. Cl. D14—3

FIG. 4.

FIG. 5.

FIG. 1 is a perspective view of a roadster showing my new design;

FIG. 2 is a front view thereof;

FIG. 3 is a side view thereof;

FIG. 4 is a top view;

FIG. 5 is a rear end view thereof.

I claim:

The ornamental design for a roadster, substantially as shown.
